UNITED STATES PATENT OFFICE.

JAMES S. THOMPSON, OF PELHAM, NEW YORK.

BRAKE-SHOE MOLD.

Application filed July 23, 1923. Serial No. 652,772.

To all whom it may concern:

Be it known that I, JAMES S. THOMPSON, a citizen of the United States, residing at Pelham, in the county of Westchester and State of New York, have invented certain new and useful Improvements in Brake-Shoe Molds, of which the following is a specification.

This invention relates to the manufacture of brake shoes without chilling, and its object is broadly to facilitate the manufacture of such brake shoes in permanent molds, by the provision of means for preventing any chilling effect upon the shoe casting from the metal of the mold, and at the same time providing a mold which can be easily and quickly opened and closed so that the casting operation can be economically performed.

20 In the accompanying drawings illustrating selected embodiments of the invention—

Fig. 1 is a central sectional view on the line 1—1 of Fig. 2.

25 Fig. 2 shows the mold of Fig. 1, partly in elevation and partly in longitudinal section.

Fig. 3 is a horizontal sectional view on the line 3—3 of Fig. 2.

30 Fig. 4 is a perspective view showing a portion of the drag in section and one member of the cope in elevation.

Fig. 5 is a transverse sectional view corresponding to Fig. 1, but showing a slightly modified construction.

35 Referring to the drawings, the mold comprises a drag member 6 and a cope comprising a relatively fixed member 7 and a slideable member 8. The drag is hinged at 9 to the fixed member 7 of the cope and is adapted to swing freely down from the cope. The cope member 8 is provided with ears 10 bored to receive the guide bars 11 mounted on the fixed member 7 of the cope and

40 projecting forward to support the member 8 of the cope in its sliding movement to and from closed position with relation to the other members of the mold. The drag member has one or more tongues 12 which are adapted to be secured in keepers 13 by removable pins 14 to hold the drag in closed position against the cope. One or more clamping bars 15 is pivotally secured to the fixed member 7 of the cope at 16 and carries a set screw 17 at its free end to engage the slideable member of the cope for holding the slideable member in proper relation to the

fixed member of the cope during the casting operation. When the mold is closed, the two members of the cope will be held rigidly clamped together and the drag member will be held rigid in its proper relation to the cope.

The parting line between the two members of the cope extends longitudinally of the mold and substantially central of the mold cavity 18, which is formed, in the construction illustrated, almost entirely in the cope. A part of the mold cavity is located in one cope member and a part in the other cope member, and the cavity comprises a recess 19 for the attaching lug 20 and side extensions 21 of said recess to accommodate the ends of the core 22, which is assembled with the lug 20 to form the opening in the lug during the casting operation. The walls 20 of the extensions 21 and the ends of the core 22 may be shaped in any manner desired to cooperate to support the core preliminary to and after the mold is closed. Since a part of the mold cavity is formed in each member of the cope, it is apparent that the core 22 can be inserted into the part of the mold cavity in either of said members of the cope while the members are open, and when the mold is closed, the core 22 will be supported in the parts of the cavity in both members of the cope. A suitable reinforcing back 23 is preferably engaged with the lug 20 and is secured by wires 24 to the core 22, so that the lug, the core and the back may be assembled as a unit and inserted in one or the other cope member preliminary to closing the mold.

The foregoing structure is more particularly described in my co-pending application, Serial No. 652,771, filed July 20, 1923, and need not be described here with greater particularity.

In that application I have shown and described a permanent mold for the manufacture of integral composite brake shoes having chilled sections produced by the chilling effect of the metal members of the mold, but this form of mold is adapted for making shoes without chilled sections, and for that purpose, I provide all the walls of the mold cavity with a facing of refractory material. In the drawings I have shown sections of refractory material set in the drag member and in the two members of the cope, but instead of these sections I may apply the re-

refractory material in the form of coating sections. One section 25 of refractory material on the drag forms the bottom wall of the mold cavity and extends from end to end thereof. Two complementary sections 26 and 27 are arranged in the cope to form the top, sides and end walls of the mold cavity. Each of these sections 26 and 27 comprises a side wall and parts of the top wall and both end walls of the mold cavity. Thus the entire mold cavity is formed by walls of refractory material and the shoe casting is protected throughout from the chilling effect of the metal in the mold. At some convenient place in the cope I provide a pouring gate 28 and I also provide the cope with one or more openings filled with soft sand plugs 29 to permit the escape of gases during the casting operation.

In Figs. 2-4 a space is left between the top of the attaching lug 20 and the top wall of the mold cavity to permit the flow of metal therebetween, but should it be desired to leave the top of the attaching lug bare the section 26 of refractory material may be extended at 27 to engage the top of the attaching lug and prevent the flow of metal thereover.

My invention provides a simple, easily operated and compact construction and arrangement of parts for a permanent mold designed to manufacture brake shoes without chilled parts. The structure of the mold is substantial and the parts are arranged for movement in opening and closing to avoid wear of the refractory facing by abrasion. It is, of course, highly important that the refractory facing should be preserved as long as possible without undue wear so that shoes of uniform size and shape may be made without waste of material and to this end it is very desirable that provision be made for discharging the shoe without wearing or deforming the refractory facing. This is accomplished in a highly satisfactory manner in my improved mold, by first removing pins 14 to release the drag member 6 which then swings downward; the sliding member is then moved to open position, leaving the shoe casting to drop by its own weight out of the cope member 7 without injury to any part of the mold. If the shoe casting should not readily discharge from the cope member 7, it can be easily dislodged without causing any injury to the mold. With my improved mold the operation of casting brake shoes is greatly facilitated and speeded up and consequently the cost of production is lessened materially.

I have illustrated the invention in a selected embodiment which I believe will be readily understood by those skilled in the art, but I do not wish to be restricted to the use of my invention for the manufacture of this particular type of brake shoe since it can be used with satisfactory results in the production of other shoes and other castings, and I consider myself entitled to make all such changes in the form, construction and arrangement of parts as fairly fall within the scope of the following claims.

I claim:

1. A permanent mold for making castings, comprising a drag member and a two-member cope having a mold cavity therein, one member of the cope being relatively fixed and the other member being slidable, the drag member being movable relative to the cope members, a facing of refractory material on the drag and cope members and forming the walls of the mold cavity, and means for holding the mold members together during the casting operation.

2. A permanent mold for making castings, comprising a drag member and a two-member cope having a mold cavity therein, one member of the cope being fixed and the other member being slidable and the drag member being movable relatively to the cope members, a section of refractory material on the drag member forming the bottom wall of the mold cavity, and complementary sections of refractory material on the cope members together forming the side walls, the end walls and the top wall of the mold cavity.

3. A permanent mold for making castings, comprising a drag and a cope having a mold cavity therein, a section of refractory material on the drag forming the entire bottom wall of the mold cavity, and two sections of refractory material on the cope forming the side walls, the end walls and the top wall of the mold cavity.

4. A permanent mold for casting a brake shoe, comprising a drag and a two-member cope having a mold cavity therein, refractory material forming the top, sides and end walls of the cavity in the cope, said cavity comprising a recess for the attaching lug and extensions of said recess for receiving the ends of a core to form the opening in the attaching lug, and said refractory material in the cope being constructed with shoulders to cooperate with said core to support said core preliminary to and during the casting operation.

JAMES S. THOMPSON.
